CLAIM

The ornamental design for a hair clipper, as shown and described.

DESCRIPTION

FIG. 1 is a front, left, bottom perspective view of a hair clipper, showing my new design;

FIG. 2 is a rear, right perspective view thereof;

FIG. 3 is a front elevational view thereof;

FIG. 4 is a rear elevational view thereof;

FIG. 5 is a left side elevation view thereof;

FIG. 6 is a right side elevation view thereof;

FIG. 7 is an enlarged top plan view of the hair clipper; and,

FIG. 8 is an enlarged bottom view thereof.

The dashed broken lines in the figures depict portions of the hair clipper that form no part of the claimed design.

1 Claim, 8 Drawing Sheets
